UNITED STATES PATENT OFFICE.

JOSEPH BLOCK, OF NEW YORK, N. Y.

DESIGN FOR A WALL BRACKET.

Application filed February 5, 1929. Serial No. 29,945. Term of patent 3½ years.

To all whom it may concern:

Be it known that I, JOSEPH BLOCK, a citizen of the United States, residing in the borough of Manhattan, in the city, county, and State of New York, have invented a new, original, and ornamental Design for a Wall Bracket, of which the following is a specification, reference being had to the accompanying drawing, forming part thereof.

In the drawings:

Fig. 2 is a side elevation of the same.

I claim:

The ornamental design for a wall bracket as shown.

JOSEPH BLOCK.
